UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

SHUTTLE-BOX TENSION-CONTROLLING MECHANISM FOR LOOMS.

Application filed October 10, 1922. Serial No. 593,553.

To all whom it may concern:

Be it known that I, JONAS NORTHRUP, a citizen of the United States, residing at Hopedale, in the county of Worcester and State of Massachusetts, have invented certain new and useful Improvements in Shuttle-Box Tension-Controlling Mechanism for Looms; and I do hereby declare the following to be a full, clear, and exact description 10 of the invention, such as will enable others skilled in the art to which it appertains to make and use the same.

The present invention relates to an improvement in shuttle box tension controlling 15 mechanism for looms.

The object of the invention is to produce a construction for varying the resistance offered by the shuttle box to the entrance of the shuttle with the position of the lay. 20 To this end the invention consists in the mechanism hereinafter described and particularly defined in the claims.

In the accompanying drawings illustrating the preferred form of the invention, Fig. 25 1 is a sectional elevation of the lay, breast beam and associated parts of a loom illustrating the construction; and Fig. 2 is a perspective view of a number of the parts together constituting a spring bracket, its 30 supporting and securing means.

The illustrated embodiment of the invention 35 is described as follows: The loom frame 1, the lay 2, the sword 3, and the other co-operating parts of a loom, may be constructed in any usual or preferred form. The lay is provided on its under side with the dagger shaft 4 to which are secured the binder fingers 5, each carrying a binder presser 6 adjustably secured to the binder 40 fingers. The dagger shaft 4 is provided with daggers 7 adapted to engage the frog in the usual manner, and it is also provided with a spring arm 8 which is rigidly secured to the dagger shaft 4. The forward end 45 of the spring arm 8 is provided with a hook 9 to which one end of the dagger shaft spring 10 is secured. The other end of the spring is hooked onto the spring hook on the bracket 11 which is secured to the frame 50 of the loom and adapted to be adjusted to various positions in order to vary the amount of tension to which the spring is subjected, and in turn the amount of the tension on the binders, and therefore the

tension on the shuttle as it enters the shuttle 55 box. The bracket 11 is slotted at 12 to receive the bolt 13. The bracket 11 is received in a slot 14 in the washer 15, provided on its under surface with a series of radial 60 grooves 16. This washer 15 is supported against a second washer 17 which has two teeth 19 adapted to enter the radial grooves 16 in the under surface of the washer 15. The washer 17 is provided with a square 65 hole 20. The bracket 11 is bolted to an ear 21 formed on the frame of the loom, which ear is provided with a slot 22 adapted to receive the squared portion of the bolt 13. The ear 21 thereby holds the bolt 13 from 70 rotating movement and the bolt holds the washer 17 from similar movement. The projections on the latter hold the washer 15 from rotating movement. On the end of the bolt is received the washer 23 and nut 24. The bracket 11 may be moved to 75 any desired position within the limits of the slot 12 and to any angular position by loosening the nut 24 on the bolt 13, and turning the bracket 11 so as to turn the washer 16 to the desired position. The 80 bracket may be secured in a wide variety of positions of adjustment with relation to the lay so as thereby to vary the amount of force exerted by the spring on the spring arms 8 and the rate at which such pressure shall 85 be varied. Thus with the spring hook of the bracket 11 in a rearward position, the time of application of the spring pressure to the spring arms on the dagger shaft will 90 be later than otherwise.

The mode of operation of the mechanism 95 is as follows: Starting with the lay in the position shown in dotted lines in Fig. 1, the binders, through the means described, exert a minimum pressure on the shuttle. This pressure is increased as the lay beats back to the back center where it reaches a maximum, and it then decreases as the lay beats forward again. By positioning the bracket in various ways it will be observed 100 that a number of different results may be secured with respect to the friction exerted on the shuttle by the binders. For example, the tension on the shuttle may be made to decrease from the front center as the lay moves rearwardly for a certain distance, thereby affording a reduction of friction on 105 the shuttle for picking purposes. The pres-

sure may then increase to the back center, affording a maximum pressure at that point which is practically the earliest point at which the shuttle may reach the shuttle box 5 into which it is being thrown, and from such point the pressure on the shuttle may decrease as the lay moves forward, so that a tardily arriving shuttle may be subjected to a lesser resistance in the receiving shuttle 10 box. Many other arrangements and variations of the friction resistance of the shuttle may be secured by this construction.

The present invention is not broadly claimed herein, as it forms the subject of 15 the application of Clare H. Draper filed July 11, 1922, Serial No. 574,212, to which, by permission, reference may be had.

Having thus described the invention, what is claimed is:

- 20 1. Shuttle box tension controlling mechanism for looms having, in combination, a lay, shuttle boxes provided with binders, binder fingers for acting on the binders, a dagger shaft carrying the binder fingers, a spring 25 arm secured to the dagger shaft, and a spring attached at one end to the end of the spring arm and at the other end to a stationary part of the loom.
2. Shuttle box tension controlling mechanism for looms having, in combination, a 30 lay, shuttle boxes carried by the lay pro-

vided with binders, a spring arm, connections between the spring arm and the binders for causing pressure to be exerted on the binders, a spring connected with a spring 35 arm and to a stationary part of the loom for causing spring pressure to be exerted on the binder, the point of attachment of the spring to the stationary part of the loom being located at a distance from the 40 axis of motion of the lay, so that variable pressures will be exerted by the spring on the binder during the operation of the loom in accordance with the time of reception of the shuttle in a box. 45

3. Shuttle box tension controlling mechanism for looms having, in combination, a lay, a shuttle box carried by the lay, a friction contrivance for increasing and decreasing the resistance of the shuttle box to 50 the entrance of the shuttle thereto, and means for applying such frictional pressure to the shuttle having provision for adjustment so as to reduce the pressure on the shuttle during the picking, to increase it to a maximum 55 at a time when the shuttle may first arrive at the shuttle box into which it is thrown, and to thereafter decrease it so that the shuttle may be received in the shuttle box with less and less resistance after the lay 60 passes the back center.

JONAS NORTHRUP.
